By his Attorney J. Worth Osgood,

UNITED STATES PATENT OFFICE.

MORTIMER G. LEWIS, OF NEW YORK, N. Y., ASSIGNOR TO EMMERT MANUFACTURING COMPANY, OF WAYNESBORO, PENNSYLVANIA, A CORPORATION.

BENCH-VISE.

SPECIFICATION forming part of Letters Patent No. 768,810, dated August 30, 1904.

Application filed February 18, 1904. Serial No. 194,165. (No model.)

To all whom it may concern:

Be it known that I, MORTIMER G. LEWIS, a citizen of the United States, residing at New York city, in the county and State of New York, have invented certain new and useful Improvements in Bench-Vises, of which the following is a full, clear, and exact specification, reference being had to the accompanying drawings and to the letters marked thereon.

My invention has relation to bench-vises such as are ordinarily employed for clamping and holding objects to be worked upon, and particularly does it relate to those forms wherein some provision is made for accommodating different sizes and shapes of pieces of work or adjustments necessary to bring the work into convenient and proper lines to facilitate the working operations.

As most ordinarily constructed the back jaw of a bench-vise is held perfectly rigid, the front jaw being made to move toward or from this back jaw and the body of the structure being mounted in an immovable way upon the work-bench or other suitable support. Bench-vises have, however, heretofore been constructed in which one of the jaws was arranged to be adjusted in reference to the other jaw, so that the two jaws might assume positions not exactly parallel with each other in order to accommodate pieces of work of which the sides were not precisely parallel, and there have also been constructed bench-vises in which the main body of the vise was mounted, so as to turn as upon a vertical axis. The means heretofore employed for locking and holding the movable parts at the desired positions have not been found entirely satisfactory, being defective in being either insecure or liable to become disarranged or being in the way of the tools usually employed by the workman, especially as in the operation of filing.

The object of my present invention is to provide or produce a bench-vise wherein the movable or adjustable parts may be securely and accurately locked in any of the desired positions without liability of interfering with

the proper use of the vise, without danger of being disturbed while the vise is in use, and without permitting lost motion between the parts which are locked together.

To accomplish the above-named objects and to secure other and further advantages in the matters of construction, operation, application, and use, my improvements involve certain novel and useful features of invention, as will be herein first fully described, and then pointed out in the claims.

In the accompanying drawings, forming part of this specification, Figure 1 is a top or plan view of a bench-vise having my improvements applied in connection therewith, the dotted lines indicating the back jaw shifted out of parallelism with the front jaw and the front jaw moved back from its position against the face of the front jaw, as shown by the full lines. Fig. 2 is a vertical axial view, partly in section and partly in elevation, showing the vise entirely closed as when there is no piece of work clamped between the jaws, the vise having a swivel connection with the base, so that it may be turned at any angle on the base, as around a vertical line. Fig. 3 is a section and partial elevation on a plane through line *x* *x* of Fig. 1, representing in detail one manner of arranging and mounting the means for locking the vise-body at any point on the base on which it turns, this view being upon a scale enlarged beyond that of previous figures. Fig. 4 is a plan view (also enlarged beyond previous figures) of the under side of the back jaw, (shown in Figs. 1 and 2,) illustrating the location and arrangement of the removable screw-pin by which the back jaw is securely locked and held in place upon the body of the vise when it is desired to secure the back jaw in such position that it will be exactly parallel with the face of the front jaw. Fig. 5 is a plan view of a fragment of the base on which the body of the vise is mounted and swiveled, the vise being removed from the base.

In all the figures like letters of reference wherever they occur indicate corresponding parts.

To hold the back jaw in parallel relation to the front jaw, it has heretofore been proposed to employ a removable locking-pin passed from the top down through the rearwardly-extending portion of the back jaw and into the body of the vise. In this position the projecting pin is found to interfere with the proper use of the vise, particularly when the work is being filed, and not only this, but the holding-pin, being somewhat tapering, works loose, particularly when the object held is being struck, as by a hammer, and when the pin is removed the perforations for it become clogged with chippings and filings, rendering it impossible to reinsert the pin without cleaning out the openings. When the back jaw is left free to move upon its mounting, it automatically adjusts itself to the contour of the piece being clamped between the two jaws; but when it is necessary to hold the two jaws in parallel relations to each other, so that a piece may be clamped at either side of the axis of the vise, then it is necessary to hold the otherwise movable jaw with perfect rigidity. For this purpose I employ a simple screw-pin, which enters a threaded opening provided for it and cut partly in the movable head and partly in the stationary portion on which the head is mounted.

A represents the main body of a bench-vise, which may be of any desired size and shape. B is a front or traveling jaw or head mounted upon a suitable slide-bar and adjustable back and forth by any suitable arrangement of vise-screw, as C.

D is one of the vise-heads mounted and arranged to turn upon the vise-body. When not locked in position, this head automatically assumes a position suitable for clamping and holding the work, which is pressed against it by the other head, B. The preferred manner of mounting the head D upon the vise-body is indicated in Figs. 2 and 4, wherein *a* on the under part of the head D represents a circular ledge adapted to fit in and bear against a correspondingly-shaped portion of the vise-body, and *b* is another ledge concentric with the first one and fitting in a circular groove provided for it in the vise-body. The swinging or turning jaw or head D receives the pressure transmitted to it through the traveling jaw B and is held against backward movement by bearing on the vise-body at the ledges *a* and *b*. That the jaw D may move easily it is rather loosely fitted in place, so that when the two jaws are in parallel position the back jaw is not rigidly held, as is very desirable.

I tap both the body of the vise and the projection *b* at one side of the swinging jaw, and in the threaded opening thus produced I insert a locking screw-pin, as E. This locking-screw is made very slightly tapering, so that when properly seated it will operate after the manner of a wedge, forcing the swinging jaw

back to a firm bearing against the projections provided for the purpose on the vise-body. This screw is easily unturned and removed when required and as easily inserted in place for use when required. The opening for it, being entirely protected by the overhanging portion of the swinging jaw, does not become clogged or stopped up by foreign substances, as in former constructions. The threads of the screw E are preferably flat on top, and the screw itself is of rapid pitch, so that it may be properly seated without requiring too many turns; but any suitable form of screw may be provided for this purpose or any form of locking-pin which will wedge the parts and remain securely in place. When removed from the position in which it is to be employed, the locking-pin may be conveniently hung upon a projecting pin, as *c*, or otherwise disposed of.

The vise-screw shown in the drawings is intended to be operated to move the traveling head by reason of a peculiar connection between the screw and the vise-body; but this manner of connection is no part of my present invention, and so far as this invention is concerned the traveling head may be moved in any preferred way or by any preferred means.

The vise-body A is mounted upon a base-plate F in such manner that it may be turned thereon, so as to bring the work to any desired angle, being connected with the base-plate by any suitable coupling-screw, as G. When the desired adjustment has been made, it is necessary that the vise-body be locked to the base-plate in some rigid and unyielding manner and without danger of disarrangement by any use of the vise. To accomplish this unyielding locking, I provide the base-plate on the interior with radially-arranged teeth, as *d d*, the teeth extending entirely around the base-plate. A threaded stud H is mounted in a projection on the vise-body, and this stud carries at its lower end a block I, provided with teeth which will interlock with the teeth *d* on the base-plate F. The stud H is turned by a swiveled finger-piece, as K.

Being constructed and arranged for operation substantially in accordance with the foregoing explanations, my improvements will be found to answer all the purposes or objects of the invention hereinbefore alluded to.

Having now fully described my invention, what I claim as new herein, and desire to secure by Letters Patent, is—

1. In a bench-vise provided with a swinging or turning head, the combination with said head and the vise-body upon which it is mounted, of a removable wedging-pin interposed between the two and located in an opening cut partly in one and partly in the other, said pin entering the opening at the side of the vise-body and below the overhanging portion

of the swinging head, substantially as and for the purposes set forth.

2. In a bench-vise provided with a swinging or turning head, the combination with said head and the vise-body upon which it is mounted, of a removable wedging screw-pin entering a threaded opening located partly in the vise-head and partly in the swinging jaw and arranged to lock and hold the parts, substan-

tially in the manner and for the purposes set forth.

In testimony whereof I have signed my name to this specification in the presence of two subscribing witnesses.

MORTIMER G. LEWIS.
